UNITED STATES PATENT OFFICE.

GILBERT CHRISTIAN, OF DETROIT, MICHIGAN.

CARBURETOR.

Application filed October 9, 1918. Serial No. 257,522.

To all whom it may concern:

Be it known that I, GILBERT CHRISTIAN, a citizen of the United States, and residing at Detroit, in the county of Wayne and State 5 of Michigan, have invented a new and Improved Carburetor, of which the following is a specification.

This invention relates to devices for combining air and hydrocarbon vapors to constitute an explosive mixture or gas suitable for use in internal combustion engines of the type shown in my former Patents No. 1,110,041 dated September 8, 1914, and No. 1,166,112, dated December 28, 1915, and its 10 object is to provide means whereby a small amount of comparatively rich mixture or a large amount of comparatively lean mixture may be had as desired merely by changing the position of the throttle valve.

This invention consists in combination with the body, the manually adjustable tubular throttle valve, and the cylindrical nozzle having a circumferential discharge opening, of a pair of small pipes or passages 15 in the wall of the throttle valve which will conduct air and fuel vapor to the discharge opening of the carburetor when the throttle has been pressed down against the nozzle to close the normal passage for the mixed air 20 and fuel vapor. It also consists in the details of construction illustrated in the accompanying drawing and specifically pointed out in the claims.

In the drawing, Fig. 1 is a side elevation 25 of this improved carburetor. Fig. 2 is a section on the line 2—2 of Fig. 1 on a larger scale. Fig. 3 is a section on the line 3—3 of Fig. 2. Fig. 4 is a central section of the throttle valve and fuel nozzle at right angles 30 to the plane of Fig. 2.

Similar reference characters refer to like parts throughout the several views.

As in Patent No. 1,166,112, the cylindrical shell or body 1 of the mixing chamber has 45 its lower end threaded to receive the lock-nut 2, between which and the mixing chamber is clamped the bottom of the cup-shaped float chamber 3. The mixing chamber has a radial flange 4 constituting the top of the 50 float chamber and any desired means may be employed to supply liquid fuel to the float chamber and control its level.

Extending across the lower end of the 55 mixing chamber is a tubular support 5 having passages 6 communicating with the float chamber. A vertical tube 7 passes through

this support and has its ends threaded. It is also formed with small intake passages 8 that communicate with the passages 6 and also formed with small discharge passages 60 9. A tube 12 is adapted to convey hot air from any convenient source of supply, its inner end preferably fitting around the lower end of the body of the carburetor. A connector 13 is screwed onto the lower end of the tube 7 and a nut 14 on the lower end of this connector holds the tube 12 in position.

Threaded upon the tube 7 is a cup 17 whose upper portion constitutes a cylindrical flange 18. A collar 19 having a conical upper end is also threaded upon the tube 7 and extends into the flange 18 so as to leave a thin radial passage and a thin cylindrical passage from the small discharge passage 9 in the tube 7 to a circumferential discharge opening 20 at the upper edge of the flange 18, which edge is just above the level 21 of the liquid in the float chamber. The collar 19 may be locked in any position of adjustment relative to the cup 17 by means 75 of a screw 22. The tube 7, cup 17 and collar 19 constitute the fuel nozzle which has a circumferential discharge opening through which fuel may flow when the air pressure at that line is less than atmospheric. 80

Slidable within the shell 1 is a tubular throttle valve 24 having a flaring lower edge 25 that surrounds the upper end of the fuel nozzle and may be forced down onto the collar 19, as shown in Fig. 2, to close the 85 normal passage for the fuel vapor. One side of the shell 21 may be formed with a slot 26 through which passes a bolt 27 whose inner end is threaded into a hole 28 in the valve 24. The outer end of the bolt passes 90 through a cam slot 29 in the cam 30 which is pivoted on a bolt 32 at the upper end of the mixing chamber. The downward movement of the throttle valve may be limited by the set screw 33 and nut 34, carried by the 95 cam 30. These parts are substantially similar to those for the same purpose shown in my prior Patent No. 1,166,112, dated December 28, 1915.

Mounted in the tubular throttle valve are 100 two small pipes 35 and 36, the former open at both ends and extending down below the lower end of the latter, as shown in Fig. 4. and the latter having its lower end beveled and extending through the beveled lower 110 surface 25 of the tubular throttle valve that it may suck up liquid fuel from the cup 17

when in the position shown in Fig. 2. The suction necessary to raise this fuel only a fraction of an inch is very slight and quite a large proportion of air will be mixed with the fuel. The upper end of the pipe 36 has holes 37 through which the vapor will be sprayed.

The air pipe 35 extends down below the bottom of the throttle valve and ends just 10 below the openings 37 in the upper end of the pipe 36 so that air will be drawn up through the pipe 35 and thoroughly mixed with the fuel sprayed from the openings 37.

The internal diameter of the throttle 15 valve will increase upwardly in order to secure the usual action of the Venturi tube. When this valve is lowered, the amount of air passing the fuel opening 20 will be decreased and at the same time the flow of 20 fuel will decrease, a fixed quantity of air passing up the pipe 35. But when the normal flow around the collar 19 is stopped by the valve 24 engaging this collar, then a substantially constant amount of fuel will pass 25 up into the mixing chamber through the pipe 36 and air through the pipe 35 which will be sufficient to permit the engine to idle.

The proportions and details of this construction may all be varied by motive engineers without departing from the spirit of my invention set forth in the following claims.

I claim:

- 35 1. In a carburetor, the combination of a body, a fuel nozzle therein having a circumferential discharge opening, a tubular throttle valve adjustable toward and from the nozzle to control the area of the main passage for the explosive mixture, manually operable means for positioning the throttle valve, and a fuel pipe mounted in the throttle valve and so positioned that its intake end will be adjacent to the fuel discharge opening in the said nozzle when the throttle valve is at the end of its travel toward the nozzle, the fuel pipe being perforated near its opposite end to permit the escape of the fuel, and an air pipe mounted in the throttle 45 valve and so positioned that its intake end will be below the fuel discharge opening in

the nozzle when the throttle valve is at the end of its travel toward the nozzle, the discharge end of the air pipe being just below the perforations in the fuel pipe.

55

2. In a carburetor, the combination of a body, a fuel nozzle therein having a circumferential discharge opening, a tubular throttle valve adjustable toward and from the 60 said nozzle to control the area of the main passage for the explosive mixture, manually operable means to position the throttle, and a pair of pipes extending up from the lower end of the throttle and connected thereto to convey air and fuel respectively 65 when the main passage is closed by the throttle.

60

3. In a carburetor, the combination of a body, a fuel nozzle in the lower part thereof having a discharge opening, a tubular throttle valve movable vertically toward and from the nozzle to control the area of the main passage for the explosive mixture, and a pair of pipes extending up within the 70 throttle, one to convey air and the other to 75 convey fuel when the main passage is closed.

70

4. In a carburetor, the combination of a body, a fuel nozzle in the lower part thereof having a discharge opening, a tubular throttle valve movable vertically toward and from the nozzle to control the area of the main passage for the explosive mixture, and a pair of pipes extending up within the 80 throttle, one to convey air and the other to 85 convey fuel when the main passage is closed, the lower end of the air pipe extending below the fuel discharge opening in the nozzle when the main air passage is closed.

80

5. In a carburetor, the combination of a body, a fuel nozzle in the lower part thereof having a discharge opening, a tubular throttle valve movable vertically toward and from the nozzle to control the area of the main passage for the explosive mixture, and a pair of pipes extending up within the 90 throttle, one to convey air and the other to 95 convey fuel when the main passage is closed, the upper end of the fuel pipe being perforated and the upper end of the air pipe terminating just below the perforations so 100 that the air will mix with the fuel.

GILBERT CHRISTIAN.
